UNITED STATES PATENT OFFICE.

WILLIAM THOMAS CLIFFORD, OF RANDWICK, NEAR SYDNEY, NEW SOUTH WALES,
AUSTRALIA.

OVERALL-GARMENT.

1,037,206.

Specification of Letters Patent. Patented Sept. 3, 1912.

Application filed September 22, 1911. Serial No. 650,777.

To all whom it may concern:

Be it known that I, WILLIAM THOMAS CLIFFORD, a subject of the King of Great Britain, residing at Hollingsworth, Perouse Road, Randwick, near Sydney, in the State of New South Wales and Commonwealth of Australia, have invented a new and useful Improvement in Overall-Garments, of which the following is a specification.

- 10 This invention refers to over-all garments worn by tradesmen as a protection to their ordinary garments and has been specially devised in order to provide an improved over-all garment of such character that may 15 be readily applied and removed and be particularly suitable for use by shop salesmen though it may be advantageously used by all other persons desiring to protect their garments while at work.
- 20 An improved over-all garment according to this invention consists of a body portion in the form of an upper waist coat open at the front forming underlap and overlap sides to take over the body of the wearer 25 and a lower portion or apron one half of which is a continuation of or attached to one side say the overlap side of the body portion and adapted to lap over and be buttoned or fastened to the other or say the 30 underlap side of said body portion. The apron portions of the over-all may each have convenient pockets and the body portion may have sleeves or be sleeveless as desired. But in order that a practical application 35 of this invention may be readily understood the same will now be described with reference to the drawings accompanying and forming part of this complete specification in which—
- 40 Figure 1 is an elevation of an improved over-all garment according to this invention spread out and Figs. 2 and 3 are per-

spective views respectively of the garment in course of application to a wearer and on a wearer ready for use. The body portion 4 45 takes around the wearer as in Fig. 2 meeting and being buttoned or otherwise fastened in the front and the apron portion 5 for about half its width may be a continuation of one side of the body portion preferably 50 the over-lap side or be attached thereto and the other half of said apron is loose and adapted to lap over the other side of the body portion preferably the underlap side as shown in Fig. 2 and be buttoned or otherwise fastened in position as shown in Fig. 3.

The apron could be attached or be a continuation of the underlap side of the body and in this construction it would have to underlap the overlap side of the body and 60 would therefore not be so convenient as the preferred construction described above.

Having now fully described and ascertained my said invention and the manner in which it is to be performed I declare that 65 what I claim is:—

In an overall garment, in combination, an upper body portion adapted to meet and fasten in the front, and a lower apron portion adapted to extend across the front of 70 said body portion adjacent its lower edge, one side of said apron portion being permanently secured to said body portion at one side of the center thereof, and means for detachably fastening the other side of said 75 apron to said body portion at the other side of the center thereof.

In testimony whereof I have signed my name to this specification in the presence of two subscribing witnesses.

WILLIAM THOMAS CLIFFORD.
